William R. Fowler
By his Atty.

UNITED STATES PATENT OFFICE.

WILLIAM R. FOWLER, OF PHILADELPHIA, PENNSYLVANIA.

MECHANICAL TOY HOOP.

SPECIFICATION forming part of Letters Patent No. 289,523, dated December 4, 1883.

Application filed May 8, 1883. (No model.)

To all whom it may concern:

Be it known that I, WILLIAM R. FOWLER, of the city of Philadelphia, county of Philadelphia, and State of Pennsylvania, have invented an Improvement in Mechanical Toy Hoops, of which the following is a specification.

My invention has reference to mechanical toys; and it consists of a figure provided with movable arms or legs, or both, carried on the end of a stick, and combined with a suitable hoop-wheel provided with cams to actuate said arms or legs, whereby the said figure and hoop or wheel, when pushed along the ground, represent a boy or girl rolling a hoop, and in details of construction, all of which are fully set forth in the following specification and shown in the accompanying drawings, which form part thereof.

Toy hoop-sticks have been made with the figure of a man, which, when rolled along the ground, causes the arms and legs of the figure to move as in the act of walking; but to my knowledge no toy has been made to represent a boy or girl rolling a hoop in which the arm carrying the hoop-stick strikes the hoop, and in such a toy the figure must be larger than the hoop.

In the drawings, Figure 1 is a side elevation of my improved toy, and Fig. 2 is a side elevation of the actuating mechanism detached.

A is the hoop or wheel, which, for cheapness, may be made of a piece of wire bent round, with an arm, B, extending into the center, which then may be bent again at right angles to form the sleeve C. This sleeve C is carried on a bearing, D, having a socket, E, in which the end of the handle F is secured.

G are cam projections secured to the end of the sleeve C, and are arranged to actuate the

legs I, which are pivoted to the body H at J, the said body being carried by the bearing D. These legs I, near their fulcrum J, are notched, as at K, forming a projection, k, which, during the rotation of the wheel A, is struck by the cam projections G, causing the legs to be alternately thrown backward, to imitate a boy running. The legs are not quite long enough to touch the ground, being designed to work freely in the air.

L is a pivoted arm, which is provided with a hoop-stick, M. This arm is vibrated by a rod, N, which is in connection with one of the legs I, and is thereby made to strike the hoop rapidly as the toy is pushed over the ground. I do not limit myself to the exact construction shown, as it may be modified in various ways without departing from my invention.

I am aware of the patent to Cleveland, No. 85,727, of 1869, and claim nothing therein shown or described.

Having now described my invention, what I claim as new, and desire to secure by Letters Patent, is—

As a new article of manufacture, a mechanical toy which consists of a wheel adapted to be propelled along the ground, in combination with a figure located wholly on one side of said wheel, and provided with a pivoted arm carrying a hoop-stick, and mechanism actuated by the rotating wheel to cause said arm to strike the hoop with said stick as in the act of rolling the hoop, substantially as and for the purpose specified.

In testimony of which invention I hereunto set my hand.

WILLIAM R. FOWLER.
